UNITED STATES PATENT OFFICE.

FRED M. KILFOYLE, OF STORRS, UTAH.

LETTER FILE.

1,427,397.

Specification of Letters Patent. Patented Aug. 29, 1922.

Application filed March 13, 1922. Serial No. 543,396.

To all whom it may concern:

Be it known that I, FRED M. KILFOYLE, a citizen of the United States, residing at Storrs, in the county of Carbon and State 5 of Utah, have invented a new and useful Letter File, of which the following is a specification.

This invention relates to a letter file, one of its objects being to provide means where- 10 by a stack of letters or other loose sheets can be held together securely without the neces- sity of punching holes therein, the gripping means employed being adjustable for engag- ing the stack of papers at any desired point 15 between the ends thereof so that it is possible to so hold the sheet that the ends thereof can be turned back readily for inspection with- out the necessity of detaching the sheets from each other.

20 A further object is to provide a letter file the parts of which can be readily disconnected so as to be stored within a small space while being shipped or while in stor- age.

25 A further object is to provide gripping means which distributes the strain through- out the width of the sheet when it is pulled, thus reducing to the minimum the danger 30 of tearing the sheet while it is being in- spected.

With the foregoing and other objects in view which will appear as the description 35 proceeds, the invention resides in the combi- nation and arrangement of parts and in the details of construction hereinafter 40 described and claimed, it being understood that, within the scope of what is claimed, changes in the precise embodiment of the invention shown can be made without de- parting from the spirit of the invention.

In the accompanying drawings the preferred forms of the invention have been shown.

In said drawings

45 Figure 1 is a perspective view showing the letter file in use.

Figure 2 is an elevation of one of the stop clips.

50 Figure 3 is a section through one end of the eccentric gripping roll.

Figure 4 is a perspective view of a portion of a modified form of roll holder.

55 Referring to the figures by characters of reference 1 designates a board constituting the backing of the holder and secured to one end thereof is a tongue 2 having an open-

ing 3 whereby the board can be suspended from a nail or the like when not in use. Spring clips 4 straddle the end of the board and have stop fingers 5 extending upwardly 60 from the board and against which the loose sheets or letters indicated at L can be stacked on the board.

Extending transversely under the board is a cross strip 6 the ends of which are in- 65 turned as at 7 so as to straddle the side edges of the board. These inturned ends have standards 8 projecting therefrom and one edge of each standard is provided with obliquely disposed notches 9. The edges of 70 the inturned portion 7 are bent outwardly as at 10 so that the strip 6 can be slid readily along the board 1 without biting thereinto.

A gripping roll 11 formed of hard rubber, of wood, or of any other suitable material 75 is arranged transversely of the board and seated in each end of this roll is a pin 12 preferably provided with barbs 13 whereby it will be held securely in the roll. The pin has a radial arm 14 seated in a groove 15 80 in the end of the roll so that the pin is thus held against rotation, and extending outwardly from this arm is a stud 16 preferably provided at its inner end with a collar 17. The studs 16 at the two ends of 85 the roll are in alignment and are adapted to be seated within the notched standards 8 so as thus to constitute eccentric bearings for the roll. After the sheets have been stacked on the board 1 the studs 16 are inserted in 90 certain of the notches so that by rotating the roll it will swing downwardly on the sheets and bind them tightly to the board. As the stack of sheets increases in thickness 95 the roll can be adjusted upwardly between the standards. By shifting the strip 6 the roll can be caused to grip the sheets at any point desired.

Instead of using the standards shown in Figure 1 both the standards and the cross strip can be made of wire as shown in Figure 4. The cross strip is made up of parallel wires 18 inturned as at 19 to straddle the sides of the board and these inturned portions merge into an upstanding loop 20 105 forming a standard. The upper end of the loop is spread open to provide an eye 21 and one of the members of the loop is bent to form notches 22, it being understood that the opposed members of the loop normally 110 contact. With this form of standard the stud 16 after being inserted into the eye

21 can be pressed downwardly to position within any one of the notches 22 without being withdrawn from engagement with the standard. The two wires 18 can be held 5 properly spaced by metal strips 23 if so desired.

When the device is not in use the several parts can be separated and can be compactly wrapped as will be obvious.

10 What is claimed is:—

1. A letter file including a board, standards adjustable along the sides of the board, and an eccentrically mounted gripping roll adjustably supported by the standards.

15 2. A letter file including a board, connected standards adjustable along opposed edges

of the board, an eccentrically mounted gripping roll detachably and adjustably connected to the standards.

3. A letter file including a board, connected standards adjustable along opposed edges of the board, an eccentric gripping roll detachably and adjustably connected to the standards, and adjustable stop devices detachably connected to the board. 20 25

In testimony that I claim the foregoing as my own, I have hereto affixed my signature in the presence of two witnesses.

FRED M. KILFOYLE.
